A. M. BULLARD.

SELECTOR.

APPLICATION FILED MAY 3, 1907.

Patented Aug. 11, 1914.

UNITED STATES PATENT OFFICE.

ALBERT M. BULLARD, OF NEW YORK, N. Y., ASSIGNOR TO WESTERN ELECTRIC COMPANY, OF CHICAGO, ILLINOIS, A CORPORATION OF ILLINOIS.

SELECTOR.

1,106,922.

Specification of Letters Patent. Patented Aug. 11, 1914.

Application filed May 3, 1907. Serial No. 371,596.

To all whom it may concern:

Be it known that I, ALBERT M. BULLARD, citizen of the United States, residing at New York, in the county of New York and 5 State of New York, have invented a certain new and useful Improvement in Selectors, of which the following is a full, clear, concise, and exact description.

My invention relates to selectors and particularly to the mechanism for advancing 10 the ratchet or equivalent movable part thereof which may control or more preferably carry the movable contact, said contact being adapted in its travel to establish electrical connection with a stationary terminal, and my object is to provide improved and 15 simplified mechanism of this character which will be capable of advancing the ratchet at a high rate of speed.

Generally speaking, my invention contemplates an arrangement whereby the retaining and stepping pawls are both normally out of engagement with the ratchet, and the provision of electro-responsive 20 means for bringing the retaining pawl into engagement with the ratchet and thereby permitting the movement of the stepping pawl into engagement with the ratchet, so that it may be operated by a suitable electro-responsive driving device, such as a stepping magnet, to effect the advance of 25 the ratchet. By virtue of this construction, the stepping pawl during its period of activity is continuously in correct operating 30 position, that is, in direct engagement with the ratchet, so that its travel is not more than that required to advance the ratchet one tooth and then retire and engage the next tooth, this result being obtained with- 35 out sacrifice of the valuable feature of restoring the ratchet and thereby its associated contact at any time by merely de- 40 driving the magnet controlling the retaining pawl of current.

I will describe my invention more particularly by reference to the accompanying drawing which represents my invention embodied in an automatic telephone exchange selector.

The contact arm 1 of the selector 50 shown is adapted to be advanced over the line terminals by means of a ratchet 2 suitably supported within the frame of the device. A retaining pawl 3 is provided for 55 the ratchet and its movement is controlled

by the armature of the retaining magnet 4, being preferably pivoted upon an extension of the armature of said magnet as shown, said retaining pawl being brought into engagement with the teeth of the ratchet when 60 the armature of the retaining magnet is attracted.

A stepping pawl 5 is provided for the ratchet, means being provided under the control of the armature of the retaining 65 magnet for normally maintaining said stepping pawl out of engagement with said ratchet. The stepping pawl is preferably pivoted upon an extension of the armature of the stepping magnet 6, and may carry a 70 pin 7 at one side of its pivot adapted to be engaged by an arm 8, carried by the extension of the armature of the retaining magnet, when said armature is retracted, to maintain the stepping pawl away from the 75 ratchet.

A spring 9 is provided adapted, when the armature of the retaining magnet is attracted and the arm 8 thereby withdrawn from engagement with the pin 7, to move 80 the stepping pawl into engagement with the ratchet, said spring preferably extending between the stepping pawl and the extension of the armature of magnet 6. Thus when the stepping pawl is released and the armature of magnet 6 is vibrated, the spring 9 will at all times maintain the stepping pawl 85 in engagement with the ratchet during its advance movement and its retiring movement, so that the armature of magnet 6 need 90 take but very short movements, and the ratchet may thereby be advanced at a very high speed.

When the retaining magnet 4 is deprived of current, the armature thereof removes the 95 retaining pawl from engagement with the ratchet and the arm 8 engages the pin 7 to withdraw the stepping pawl from the ratchet, whereupon the contact arm and ratchet may be restored to normal position 100 by suitable spring mechanism.

I claim:—

1. The combination with a ratchet, of a retaining pawl for said ratchet, a retaining magnet, an armature for said magnet 105 adapted when attracted to hold said retaining pawl in engagement with said ratchet, a stepping magnet, an armature therefor, a stepping pawl pivoted to said armature, means controlled by the armature of the re- 110

taining magnet for maintaining said stepping pawl out of engagement with said ratchet whenever the retaining magnet is in its normal position, and a spring adapted 5 when said armature of the retaining magnet is attracted to move said stepping pawl into engagement with said ratchet, whereby the ratchet may be advanced at a high speed upon the operation of said stepping magnet.

10 2. In a step-by-step device, the combination with a ratchet of a stepping magnet for advancing said ratchet, and retractive means for returning said ratchet to normal, an armature for said stepping magnet, a pawl 15 carried by said armature and adapted to engage said ratchet to advance the same, a retaining magnet, an armature therefor and a retaining pawl carried by said armature adapted when the magnet is actuated to 20 prevent the return of said ratchet under the influence of said retractive means, and means carried by the armature of said retaining magnet for lifting the stepping pawl out of engagement with said ratchet

when the retaining magnet is deenergized 25 and for maintaining said stepping pawl out of engagement with said ratchet until said retaining magnet is again energized.

3. In combination with a ratchet, retractive means for moving said ratchet in one direction, a pawl, an operating magnet therefor for moving said ratchet in the other direction, a pawl and operating magnet therefor for maintaining said ratchet in any of its off-normal positions during the stepping 35 movement of the first named pawl, the armature of said retaining magnet serving when retracted to lift both said pawls out of engagement with said ratchet and to maintain them so until said retaining magnet is 40 again energized.

In witness whereof, I hereunto subscribe my name this 29th day of April A. D. 1907.

ALBERT M. BULLARD.
